UNITED STATES PATENT OFFICE.

MENZO M. BENSTER, OF GETTYSBURG, SOUTH DAKOTA.

SASH-CORD FASTENER.

1,215,101.

Specification of Letters Patent.

Patented Feb. 6, 1917.

Original application filed February 16, 1915, Serial No. 8,485. Divided and this application filed July 23, 1915. Serial No. 41,488.

To all whom it may concern:

Be it known that I, MENZO M. BENSTER, a citizen of the United States, and a resident of Gettysburg, in the county of Potter and State of South Dakota, have made certain new and useful Improvements in Sash-Cord Fasteners, &c., of which the following is a specification.

My invention relates to improvements in sash cord fasteners and guides used in window construction, the present application being a division of my application for patent for window, Serial No. 8,485, filed Feb. 16, 1915, and has for its object to provide improved sash cord attaching and detaching means whereby a window sash can be quickly put in place and removed into a room with equal facility for cleaning, repair, etc.

My invention consists in certain particular features of construction, arrangement, and combination of parts as will be herein-after described and pointed out in the claims, reference being had to the accompanying drawing, in which,

Figure 1 is a vertical sectional view of my improvements, as applied.

Fig. 2 is a top plan view of the meeting rail of a lower sash and a section through the sash cord.

Fig. 3 is a vertical sectional view of a window frame and sash cord guide.

Fig. 4 is an end view of the same.

Fig. 5 is an underview of the thimble and cord latch, when occupying the position shown in Fig. 3.

Fig. 6 is a diagrammatic view, showing complete frame and with my improvements applied.

In carrying out my invention, the sash cords M which pass over the guide pulleys L mounted on top the frame A at each corner and journaled within the housing or shields 12, are provided at one end with a tubular metal ferrule or sleeve M² and riveted thereto; the other end of the cord is to be attached to a conical weight N which has a tapering bore larger at the lower end than at the upper end so that the ferrule

M' which is cylindrical will be wedged tightly in the tapering bore when tension is put on the cord or it is pulled upwardly; by making the weight conical as shown, it will have greater specific gravity at its lower end and assume a vertical position at all

times, and hence maintain the cord in a vertical position so that it cannot buckle or jam; the end of the cord which is to be attached to the sash is provided with a tubular sleeve M² which is secured to the cord by a pin M³, which projects across the lower end of the sleeve and beyond the same at each side. To attach the cord to the sashes I provide the bracket O secured to the sashes at each upper corner upon the top of the top rail thereof. This bracket is provided with substantially L shaped up-standing ears O' provided with undercuts O² into which are shoved the projecting ends M³ of the pin securing the sleeve M² to the cord M.

To allow the ends M³ to be shoved into place in the bracket O, I provide a plate spring keeper O³ fastened at one end to the base of bracket O, the free end being notched to provide fingers o which will engage the sleeve M² when it has been forced between the ears O' and into the undercuts O². To release the cord the spring keeper is forced downwardly when the sleeve with the projecting pins M³ can be slid out of the bracket; this end of the cord is then allowed to run upwardly until the upper end of the sleeve M² extends into a circular recess A' in the upper cross member of the frame and this recess is provided with a thimble A² of metal or other suitable material to prevent the cord from chafing and wearing the wood, and to form a stop for the pins M³ at lower end of sleeve M²; the pin which secures the sleeve to the cord passes across the lower open end of the sleeve and to again attach the cord to the sashes, a rod having a hook is used thus; the hook is caught over the cross pin and the sleeve drawn downwardly until it can be reached by hand when it is again shoved into place on the bracket O, the spring keeper O³ holding it in place and preventing accidental displacement. The shield or housing prevents the sash cords from leaving the pulleys L and becoming jammed in the frame as frequently occurs in the ordinary sash frame and cord equipments.

I claim:—

1. In a window comprising a frame, a sliding sash and cord guiding means at the top of the frame, said means including a vertical opening to guide the cord and enlarged at its lower end, a lining thimble in

105

110

said enlargement, a sash cord and a fastener therefor consisting of a tubular sleeve secured to one end of said cord, lateral projections at the lower end of the sleeve, the sash carrying a spring catch secured to the upper rail thereof adapted to be engaged by said lateral projections on the sleeve to detachably couple the sash and cord.

2. In a window including a slideable sash and a frame provided with a cord guide at its upper corner, a sash cord running through the top of the frame at the upper corner, a metal sleeve rigidly secured at the opposite end of the sash cord and provided with lateral projections adjacent its lower end, and a latch secured to the upper face of the top rail of the sash and comprising

ing a base, spaced and undercut vertical ears adapted to receive and hold the projections of the sash cord, and a spring keeper secured to the latch base to retain the sleeve between the spaced ears.

3. A sash cord fastener for securing a sash cord to the top rail of a sash, consisting in combination of a tubular sleeve secured to one end of the cord, said sleeve having lateral projections adjacent its lower ends and a latch member consisting of spaced apart undercut ears to receive the said projections, and means for preventing removal of the projections from the undercut ears.

MENZO M. BENSTER.
